United States Patent Office.

HELEN EKIN STARRETT, OF LAWRENCE, KANSAS.

Letters Patent No. 100,207, dated February 22, 1870.

IMPROVED FASTENING FOR OVERSHOES.

The Schedule referred to in these Letters Patent and making part of the same.

To all whom it may concern:

Be it known that I, Mrs. HELEN EKIN STARRETT, of Lawrence, in the county of Douglas, and State of Kansas, have invented a new and improved Fastening for Rubber Shoes; and I do hereby declare that the following is a full, clear, and exact description of the construction and operation of the same, reference being had to the accompanying drawings making a part of this specification, in which—

Figure 1 is a longitudinal vertical section, showing the loop fastened in the insole, and the strap passed through the loop, and through the elastic cord; and

Figure 2 is a transverse vertical section, showing the strap glued to the inside of the mouth of the shoe, and also the strap passed behind the counter.

This invention consists in straps secured at their lower ends to the inside of an overshoe, and intended to be fastened over the top of the foot in any suitable manner, for the purpose of retaining the shoe thereupon.

In the drawings—

A is the shoe, and

a; the strap.

In fig. 1, the strap is shown as passing under a loop, *b*, strongly secured in the insole *b'*, before the latter is glued to the shoe.

The ends of the strap are drawn up over the wearer's foot, and secured together by buckle, button, hook, loop, or the like.

An elastic band, *b'*, affixed transversely to the upper side of the insole, serves to retain the strap when not in use.

In fig. 2, two other methods of securing the strap to the shoe are shown, one of which consists in gluing two short straps *a a*, one to either side of the mouth of the shoe, said straps to be fastened over the top of the foot in a similar manner, as before described.

The other method is that of a continuous strap, *a*, passed behind the counter or under the heel, and fastened over the top of the foot.

Having thus described my invention,

What I claim as new, and desire to secure by Letters Patent, is—

The combination of the rubber overshoe A and strap *a*, when the latter is arranged to pass under the heel of the wearer, and adapted to be folded and secured to the inner sole of the shoe, when not required for use, as and for the purpose set forth.

MRS. HELEN EKIN STARRETT.
